(57) **CLAIM**

The ornamental design for a baby bottle with base, as shown.

DESCRIPTION

FIG. 1 is a front perspective view of a baby bottle with the base showing my new design.

FIG. 2 is a top view thereof.

FIG. 3 is a bottom view thereof.

FIG. 4 is a side view thereof. The opposite side view is substantially identical.

FIG. 5 is a back view thereof.

FIG. 6 is a front view thereof.

FIG. 7 is an exploded view of the baby bottle; and,

FIG. 8 is an exploded view of the base.
